UNITED STATES PATENT OFFICE

2,200,501

ILLUMINATION CONTROL SYSTEM

Richard B. Hunter, Shorewood, Wis., assignor to
 Cutler-Hammer, Inc., Milwaukee, Wis., a corporation of Delaware

Application July 15, 1939, Serial No. 284,655

4 Claims. (Cl. 175—312)

This invention relates to improvements in illumination control systems and more particularly to illumination control systems comprising a plurality of lamp circuits with provision for presetting a plurality of intensities of illumination of each circuit and effecting transition from one preset intensity to another at a desired rate by the operation of a master fader control potentiometer while at the same time affording selective individual control of the various individual lamp circuits.

An object of the invention is to provide a system of the aforementioned character including for each lamp circuit a relay which responds selectively to a plurality of control voltages impressed thereon to vary the illumination intensity of its respective lamp circuit in accordance with such response.

Another object is to provide a system including individual circuit and master control devices providing for presetting of selective values of the illumination intensity of a plurality of lamp circuits and simultaneous transition from one preset intensity to another of all of said lamp circuits by means of a master control fader.

Another object is to provide a system wherein a plurality of individual lamp circuit controllers may be grouped selectively for joint control from one master controller.

Other objects and advantages will hereinafter appear.

The accompanying drawing is a diagram of a system incorporating the invention.

The system as shown comprises two lamp circuits 1 and 2. Power is supplied to the lamp circuits and to the control circuits from the alternating current bus bars L¹, L². Each of the lamp circuits receives current through an autotransformer dimmer 3 which has its primary winding connected across lines L¹ and L² and which is provided with a sliding contact 4 by means of which a variable secondary voltage of the transformer may be impressed on the lamp circuit. The sliding contact or brush 4 connects the various taps of the transformer winding with the contact bar 5 to which one terminal of the lamp circuit is connected while the other terminal of the lamp circuit is connected to the line L². The brush 4 may be moved along the transformer taps and bar 5 by a screw 6 which is driven by a reversible motor 7, the latter being provided with reversing windings and being controlled by relay 8. The relay 8 comprises a lever 8^a pivoted at its center and carrying at each end thereof a magnet core 8^b, said lever being normally biased

to a center or horizontal position, as shown, in any suitable manner. The cores are surrounded by polarizing coils 8^c and scene control coils 8^d and 8^e respectively. The lever 8^a is provided with a contact arm 8^f which when the lever rotates makes contact with stationary contacts 8^g and 8^h respectively, to thereby energize one or the other of the reversing windings of motor 7 and to cause the latter to rotate in a corresponding direction. The circuit arrangement for the lamp group 2 and any other additional light circuits is the same as that thus far described.

The system further includes two fader control masters 12 and 13 respectively, each comprising a potentiometer rheostat or autotransformer 12^a and 13^a respectively, which are connected across the lines L¹ and L² and which are provided with sliding contacts 12^b and 13^b, respectively. The sliding contacts or brushes 12^b and 13^b are connected with each other mechanically to move simultaneously in opposite directions relative to the lines L¹ and L² over the potentiometers 12^a and 13^a respectively, so that when one of the brushes moves, for instance, in the direction from line L¹ to line L² the other brush moves in the reverse direction.

Lamp circuit 1 is provided with two scene potentiometers 14 and 15, respectively, the potentiometers being connected between line L¹ and the brushes 13^b and 12^b respectively, and being provided with sliding contacts or brushes 14^b and 15^b, respectively. The potentiometer receiver rheostat 16 comprises a resistance 16^a which is connected between the lines L¹ and L² and a sliding contact 16^b which makes contact between a variable point of the rheostat 16^a and a contact bar 16^c. The contact 16^b is driven to move synchronously with the contact brush 4 so that the position of the former corresponds to the position of the latter and therefore to the brilliancy of the lamps 1. The coils 8^d are connected between the contact brush 14^b and line L¹ and the coils 8^e are connected between the contact brush 15^b and the line L¹, while the coils 8^c are connected between line L² and the contact bar 16^c. The coils 8^c are wound so that the current flowing therethrough produces equal up and down pulls on the respective armatures, both tending to rotate the relay lever in the same direction to thereby close the corresponding motor circuit and cause rotation of the latter to decrease the voltage impressed on the lamps and decrease the voltage and current of the coils 8^c. The coils 8^d and 8^e are wound so that they tend to

cause rotation of the armature lever in a given direction, while the coils 8^c tend to reverse said rotation. Hence the relay is balanced and its contacts are open as long as the aggregate pull from coils 8^d and 8^e is equal to that from the coils 8^c. If the brilliancy of the lamps is to be increased it is only necessary to increase the voltage impressed upon coils 8^d and/or 8^e. This causes the relay to close the motor circuit to increase the lamp voltage and to simultaneously increase the current in the coils 8^c until the pull is again balanced when the relay opens its contacts and the motor is disconnected. The action is reversed if the lamp voltage is to be lowered.

Assuming that the system is connected as shown and described and the brushes 12^b and 13^b are in their extreme right hand position; no voltage is impressed upon the potentiometers 15 and full line voltage is impressed upon the potentiometers 14 so that the latter are in sole control and the lamp intensity of each lamp circuit depends upon the setting of the brushes 14^b. If it is now desired to enact scene 2 the potentiometers 15 are adjusted to the desired new value, whereupon the fader master brushes 12^b and 13^b are moved to the extreme left hand position which reduces the voltages on the potentiometers 14 to zero and impresses full line potential on the potentiometers 15, thereby subjecting the motors 7 and the corresponding lamp circuits to the control of the potentiometers of scene 2.

It is of course possible, if desired, to leave the brushes 12^b and 13^b in an intermediate position in which case the voltage controlling the illumination intensity of the lamp groups is a resultant of the two voltages of the potentiometers 14 and 15. It is possible of course to further expand the system shown by other well known means such as group and grand master potentiometers of any known type suitable for this type of controller.

What I claim as new and desire to secure by Letters Patent is:

1. A control system comprising a circuit to be controlled, a controller for said circuit including a voltage regulator adapted to supply a voltage varying with an operating value of said circuit and an electromagnetic relay having a balancing winding responsive to said voltage and a plurality of control windings cooperating with said balancing winding, a plurality of sender voltage regulators, one for each of said plurality of control windings, each regulator providing for a variable ratio between its input and output voltage and arranged to impress its output voltage upon the respective control winding, and a pair of faders adapted to increase the input voltage of one and simultaneously decrease the input

voltage of another of said plurality of sender voltage regulators.

2. A control system comprising a circuit to be controlled, a controller for said circuit including a voltage regulator adapted to supply a voltage varying with an operating value of said circuit and an electromagnetic relay having a balancing winding responsive to said voltage to thereby effect a change in said operating value and a plurality of control windings adapted to counteract the effect of said balancing winding, a plurality of sender voltage regulators, one for each of said plurality of control windings, each regulator providing for a variable ratio between its input and output voltage and arranged to impress its output voltage upon the respective control winding, and a pair of faders adapted to increase the input voltage of one and simultaneously decrease the input voltage of another of said plurality of sender voltage regulators.

3. A control system comprising a circuit to be controlled, a controller for said circuit including a potentiometer adapted to supply an output voltage varying in accordance with the voltage of said circuit and an electromagnetic relay having a balancing winding responsive to said output voltage and a pair of control windings adapted to counteract the effect of said balancing winding, a pair of sender potentiometers, one for each of said control windings, each potentiometer adapted to impress its output voltage upon the respective control winding, and a pair of faders adapted to simultaneously vary the input voltages of said sender potentiometers in opposite directions.

4. In an illumination control system affording individual and joint control of the intensity of illumination of a plurality of groups of lamps for the enactment of a plurality of scenes of illumination, comprising for each group of lamps intensity control means including a potentiometer adapted to supply an output voltage varying in accordance with the intensity of said lamps and an electromagnetic relay having a compensating winding responsive to said output voltage, a pair of control windings adapted to counteract the effect of said compensating winding and a pair of sender potentiometers, one for each of said control windings and each adapted to impress its output voltage upon the respective control winding, and a pair of faders adapted to increase the input voltages of one of each of a plurality of said pairs of sender potentiometers and simultaneously to decrease the input voltages of the other of each of said plurality of said pairs of sender potentiometers.

RICHARD B. HUNTER.
